UNITED STATES PATENT OFFICE.

LEO KELLER, OF NEW YORK, AND SAMUEL B. WILLIAMS, OF BROOKLYN, NEW YORK,
ASSIGNORS TO WESTERN ELECTRIC COMPANY, INCORPORATED, OF NEW YORK,
N. Y., A CORPORATION OF NEW YORK.

TELEPHONE-EXCHANGE SYSTEM.

Application filed March 31, 1923. Serial No. 628,988.

To all whom it may concern:

Be it known that we, LEO KELLER and SAMUEL B. WILLIAMS, citizens of the United States, residing at New York, in the county of New York, and Brooklyn, in county of Kings, respectively, and State of New York, have invented certain new and useful Improvements in Telephone-Exchange Systems, of which the following is a full, clear, 10 concise, and exact description.

This invention relates, in general, to telephone exchange systems and more specially to systems employing machine switching apparatus for the establishment of conversational connections.

The object of the invention is an improved arrangement for distributing or apportioning the traffic to the switching apparatus of the exchange.

20 A feature relates to the provision, in a system where the switches are divided into groups with a controlling mechanism allotted to each group, of means for diverting the traffic normally incoming to a given 25 group of switches to other switches when trouble occurs in the corresponding controlling mechanism.

Another feature relates to the provision 30 of an arrangement whereby the controlling mechanism allotted to a group of switches alters the control of such switches to divert calls to an operator's position which normally would be directed into a succeeding group, providing trouble exists in the equipment of 35 such succeeding group.

Other and further advantages of this invention will be pointed out in detail in the description hereinafter and also in the appended claims.

40 Considering the drawing, Figs. 1 to 14, inclusive, when arranged in the order illustrated in the diagram of Fig. 16 disclose the details of a telephone system incorporating the features of the present invention.

45 Fig. 1 illustrates a line switch of the coordinate type in which the subscriber's lines terminate, and also two of a number of trunks outgoing to a district selector switch.

50 Fig. 2 shows certain control elements associated with the outgoing trunk and also illustrates a trouble operator's position.

Fig. 3 discloses a district selector switch of

the coordinate type in which terminate the trunks incoming from the line switches.

Fig. 4 illustrates a coordinate group selector switch in which terminate the trunks incoming from the district selectors.

Fig. 5 shows a coordinate connector switch for completing connections to the subscriber's lines.

Fig. 6 represents a sender selector switch also of the coordinate type.

Figs. 7, 8 and 9 depict one of a number of register senders.

Fig. 10 shows a sender connector device 65 for connecting any of the plurality of senders with the common marker or selection controlling device.

Figs. 11 and 12 illustrate the marker controlling device.

Fig. 13 shows a sender connector device for connecting the line marker with any of the several register senders. This figure also shows the testing relays for testing the condition of the trunks incoming to the group selector and connector switches together with certain control elements of the line marker.

Fig. 14 discloses the remainder of the line marker.

Fig. 15 is the schematic showing of a telephone system employing switches and controlling apparatus of the type shown in detail in the other figures.

Referring to Fig. 15, the subscribers' lines entering the exchange appear as calling lines in a number of coordinate line switches 1500, 1501 and 1502. The rectangle 1500, for example, may represent a plurality of switches which receive a given group of calling lines. Likewise, rectangles 1501 and 1502 represent other switches receiving other groups of calling lines. The trunks outgoing from the switches 1500 are distributed in any suitable manner among a plurality of groups or divisions, each division consisting of a plurality of district or first group selector switches.

The rectangles 1503, 1504 and 1505 each represent a plurality of district selectors 100 which all taken together comprise the first group or division of switching equipment. Certain of the trunks outgoing from the line switches 1500, 1501, 1502 are directed into

the district switches of this first division. Similarly, other trunks outgoing from the line switches are distributed among the district selectors of a second group or division comprising district selectors 1506, 1507 and 1508. Likewise, as many other divisions may be provided as is desirable.

The subscribers' lines may be divided into a number of groups of called lines, known as terminal line groups. One of these terminal line groups is served by a plurality of group selectors 1509 and a plurality of connector switches 1511. Another terminal line group is provided with group selectors 1510 and the connectors 1512. Each trunk outgoing from the district selectors of the first division is multiplied to all switches in that division as illustrated and leads into one of the group selectors. These trunks are so distributed that any of the district selectors may obtain access to any of the different terminal line groups.

The first division of switches is provided with a plurality of register senders 1514, 1515, etc., a single district marker 1516 and the requisite number of sender selector switches 1513. The sender selectors 1513 serve to pick out an idle one of the register senders and associate it with the trunks extending from the line switches to the district selectors of the first division. The senders are all associative with the district marker 1516, which in turn, may be associated with any one of the district switches in the first division in order to control the setting movement of such switch. Likewise, the second division is provided with similar equipment consisting of sender selectors 1517, senders 1518, 1519, etc. and district marker 1520.

The terminal line groups are provided with individual line markers 1521 and 1522 which are associative with any register sender pertaining to any division and which control the group selector and connector switches of that particular group to complete the connection through to a called line.

Should it be discovered that the district marker 1516 pertaining to the first division is in trouble or should for any reason it be desirable to prevent calls coming into the district selectors of such division, the trouble operator throws a key 1526. This key serves to render all trunks which lead into the district switches 1503, 1504 and 1505 of the first division non-selectable to the line switches. This means that the traffic incoming to the line switches will now be forced to find its way over trunks outgoing from the line switches into the district switches of other divisions. In a similar manner should trouble exist in the second, or any of the other divisions, the operator by throwing a key similar to the key 1526 would divert traffic from such division. Again should

trouble exist in one of the line markers 1521, 1522 pertaining to the terminal line groups, it is desirable to prevent the district selectors from routing calls into the terminal line group where the trouble exists. To accomplish this the operator at the trouble desk throws a key 1527 which brings about a condition in the district markers 1516, 1520, etc. whereby whenever a call is going through to the final line group concerned, the marker so controls the district switches as to route such call to an answering operator's position 1523.

General description of the system and apparatus.

The line switch 100, selector switches 300 and 400, connector switch 500 and the sender selector switch 600 employed in this system are of the coordinate type such as shown and described in the British Patent 183,436, accepted August 23, 1923, granted to the Western Electric Company, Limited, and in the patent to S. B. Williams, No. 1,517,331, granted December 2, 1924.

The subscribers' lines enter the exchange and appear in the coordinate line switches 100 in vertical rows 110 and 111, each line having access to a group of horizontal links such as the groups represented by links 106, 107, and links 108, 109. Line 101, for instance, has access to the group of links containing the links 106 and 107. Each of the outgoing trunks 114 and 115 occupies a full vertical row of contacts 112, 113 and leads to the district switches.

The trunk 114 which is shown in full appears in the district switch 300 occupying the vertical row of contacts 308. Another trunk 115 outgoing from the line switch 100 is shown occupying the full vertical row of contacts 309. District selector switch 300 also has a plurality of groups of outgoing trunks appearing in the rows 311, 312, 313, etc. Each outgoing trunk is shown having an appearance before a single one of the horizontal links 331, 332, 333, etc. These trunks are multiplied as explained to appear before corresponding horizontal links in all other district selectors of the same division.

Since the subscribers' lines are divided into a number of groups of called lines, known as terminal line groups, the trunks outgoing from the district switches are arranged in corresponding groups so that the district switches have access to any of the terminal line groups of the switching apparatus. The group of trunks appearing in the upper section 302 of the vertical row 311 in the district switch 300 lead to the group selector switches of a particular terminal line group. One of these trunks is shown leading to the group selector switch 400. The group of trunks occupying the lower section of the same vertical row may run to the group

5 selectors of the same or of a different terminal line group, as desired. Other groups outgoing from the district switches are distributed to other terminal line groups of 5 switching apparatus. In addition to these groups of trunks leading to the terminal line groups, the district switches may be provided with trunks extending in other directions. For instance, the group of 10 trunks appearing in the section 301 of the vertical row 314 lead to an answering operator's position 330.

15 The groups of trunks outgoing from the group selector 400 and from other group selectors in the same terminal group are distributed to a suitable number of connector switches. One of these connectors 500 is shown and a single trunk incoming from the selector switch 400.

20 The called subscribers' lines appear in the connector switches in groups. For example, the vertical rows 524, 525, each represents a group of subscribers' lines. Each line is accessible over a group of horizontal links. 25 The line 516 appears in the group occupying the vertical row 525 and is accessible by a group of links, two of which, 501 and 502, are shown. A second line 526 appearing in the same group is accessible by another 30 group of horizontal links 504, 505.

35 The district marker shown in Figs. 10, 11 and 12 includes two registers 1101 and 1102 which receive their registration from the controlling sender. These registers determine the setting of a multicontact relay translating device 1100 which results in the selection of one of a number of group relays 1230, 1231, 1232. These latter relays determine the selection of a group of trunks at 40 the district switches. Furthermore, the translator comprises two sets of testing relays 1200 and 1203. The set 1200 serves to test the horizontal links of the section 302 in any district selector switch of this division 45 and also to test the outgoing trunks which have access to these horizontal links. Connecting device 1202 which comprises a number of multicontact relays 1215, 1216, etc., serves to connect the set of relays 1200 with the proper group of outgoing trunks. Likewise, the other set of test relays 1203 serves 50 with respect to the set of horizontal links 301 in all switches and the outgoing trunks to which these links have access. The connecting device 1204 consisting of a number of relays 1212, 1213, etc., acts to associate the testing relays 1203 with the proper groups of outgoing trunks. Also a connecting device 1201, consisting of multicontact relays 1222, 1223, 1219, 1220, 1225 and 1226 serve 55 to connect the marker testing relays with the individual switches of the division.

60 The line marker shown in Figs. 13 and 14 includes a plurality of registers 1400, 1401 and 1402 which receive the numerical record

from the controlling sender. It also includes a multicontact relay translating device 1404 which is operated according to the settings of the registers to select the magnet 514, 515 individual to the different vertical rows of 65 outgoing lines in the connector switches. Moreover, the marker includes a multicontact relay device 1403 which serves to associate the register 1401 with a connecting device 510 individual to the proper connector switch 500. The device 510, consisting of relays 511, 512, etc., serves to associate certain test relays with the horizontal links of the group having access to the called lines of the desired units designation. In Fig. 13 70 the set of testing relays of the marker are associative through the multicontact relay connecting devices 401 and 402 with the groups of trunks outgoing from the selector switch 400 and other switches and with the 75 horizontal links of these group selectors.

Detailed description of establishment of a connection.

Consider that the subscriber of line 101 79 desires to hold conversation with the subscriber of line 516 appearing in the same central office. It may also be assumed that the directory number of line 516 is A B 1 2 3 4. When the subscriber of line 101 85 takes down his receiver a circuit is closed from battery through the winding of line relay 121, inner contact of cut-off relay 120, conductor 104, through the substation and returning over conductor 103 to ground at 90 the outer contact of relay 120. Relay 121 operates and a circuit is closed from battery through the winding of relay 129, right back contact of relay 128, left contact of relay 121, conductor 156 to ground. 95

Relays 128, 129 and 130 enclosed within the broken rectangle pertain to the vertical group of lines appearing in the row 110 of the switch 100. These relays are brought into action whenever one of the lines in the 100 corresponding group initiates a call.

Relay 129 completes a circuit from battery through the winding of relay 131, inner front contact of relay 129 to ground. Relay 129 also closes a circuit from battery through 105 the left-hand winding of relay 130, outer front contact of relay 129, left back contact of relay 135, outer right contact of relay 137, conductor 158 to ground. Relay 130 operates and closes a circuit for relay 128. Relay 128 locks through its left contact and the left contacts of relays 131 and 132 to ground. Relay 130, in operating, completes a circuit from battery through its right-hand winding and inner right contact, winding of relay 135, outer right contact of relay 137, conductor 158 to ground. Relay 135 operates and closes a circuit from battery through the winding of slow-to-release relay 136, inner right contact of relay 135, inner right back 130

contact of relay 137, conductor 158 to ground. Relay 136 closes a substitute holding circuit for relays 130 and 135 independent of the relay 137.

- 5 With relay 135 operated a circuit is closed from battery through the winding of the vertical magnet 116, outer right front contact of relay 130, left front contact of relay 135, contact of relay 136, conductor 158 to ground. The magnet 116 operates and prepares the contacts in the vertical row 110. Magnet 116 also closes a circuit from ground, through its contact, conductor 159, inner contact of relay 134, outer left contact of relay 130, right contact of relay 121, left-hand winding of relay 122 to battery. The relay 122 is a group relay individual to the group of horizontal links including the links 106 and 107. Similarly, relay 123 is a group 20 relay individual to the group containing the links 108 and 109. Relay 122 operates and closes a circuit from battery through its right-hand winding and right front contact, right back contact of relay 123 (assuming this relay to be deenergized), winding of relay 134, conductor 159 to ground at the contact of magnet 116. Relay 134 also operates in this circuit.

Another circuit is closed from battery 30 through the winding of the vertical operating magnet 118, brush 144 of allotter switch 143, contact of slow-to-release relay 139, left contact of relay 137, outer right contact of relay 135, conductor 158 to ground. It is assumed that the first one of the outgoing trunks 114 is idle at the time this call is made and that the allotter switch 143 is standing in a position to allot this trunk as shown in the drawing. The allotter switch 40 143 has a position for each of the several trunks which lead out of the line switch 100 to the succeeding district selectors. Consequently the vertical magnet 118 relative to the idle trunk 114 operates and prepares the 45 contacts of the vertical row 112. Magnet 118, in operating, completes a circuit from battery through its winding and inner contact, conductor 160, winding of relay 137, outer right contact of relay 135 to ground. 50 Relay 137, however, being shunted by the circuit above traced does not operate at this time. Magnet 118, furthermore, closes a circuit from ground through its outer contact, conductor 151, winding of the trunk 55 relay 146 to battery.

With relay 146 operated a circuit is completed from battery through the winding of relay 139, winding and contact of stepping magnet 138, brush 145, contact of relay 146 to ground over conductor 151. The stepping magnet 138 operates, interrupts its own circuit and advances the brushes 144, 145 and 154 to the next set of terminals. If the following trunk is idle the allotter switch 60 65 comes to rest, but if it is busy the switch

continues until an idle trunk is found. When the switch leaves the position shown, it opens the shunt around the winding of relay 137 and this relay operates in series with the magnet 118. Relay 137 opens the 70 circuit of relay 136 which commences to deenergize. Relay 136 being slow, holds its armatures for an interval after the release of relay 137, which is sufficient for certain operations to take place. 75

During this interval a circuit is closed from ground by way of conductor 158, inner right front contact of relay 137, outer contact of relay 134, left back contact of relay 123, left front contact of relay 122, back contact of relay 127, assuming the first link 107 is idle, winding of the horizontal operating magnet 125 to battery. Magnet 125 operates and effects a connection between the link 107 and the incoming line and also 80 between the link and the outgoing trunk 114. Immediately that this connection is established a circuit is closed from battery through the winding of magnet 125, winding of relay 127, contacts of the switch 100, over the sleeve conductor to ground at the outer contact of magnet 118. The switch is temporarily held by means of this circuit. The relay 127 however, being shunted, does not 85 operate at this time. Another circuit is 90 closed from battery through the winding of cut-off relay 120, conductor 105, through contacts of the switch, over the sleeve conductor to ground at the contact of magnet 118. Relay 120 opens the circuit of relay 100 121, which in turn, opens the original energizing circuit of relay 129.

Should another line in the same vertical group attempt simultaneously to make a call 105 while a subscriber in a succeeding vertical group is calling, his attempt to make such a call will be unsuccessful. When the line relay 121 releases it opens the holding circuit of relay 131, but since a second subscriber 110 of the same group is calling, relay 131 is held energized over a parallel circuit through the left contact of the line relay similar to relay 121. Relay 131 in remaining energized preserves the locking circuit of relay 128, which prevents the reenergization of relay 129. A second subscriber in 115 the first group, therefore, cannot succeed in making a call until all simultaneous calls in subsequent groups have been handled or until a call has been made in each one of said 120 succeeding groups. In this latter event a series circuit is closed for relay 132 through the back contacts of all relays similar to relay 129 and relay 132 operates to unlock the relay 128.

At the instant relay 146 energizes the ground potential on conductor 151 is extended through the contact of this relay over conductor 150, through the back contact of relay 204, conductor 206, thence through the wind- 125 130

ing of relay 613 to battery. Relay 613 operates and locks through its winding and inner left contact, conductor 207 to ground at the outer left contact of relay 201. Relay 613 completes a circuit from ground through its outer right contact, conductor 209, winding of slow-to-release relay 204 to battery. Relay 204 operates and applies holding ground to the conductor 150, whereby magnet 125 and relays 120 and 146 are held energized and relay 127 is energized when magnet 118 becomes deenergized. Relay 613 operates similarly to the relay 120 of the line switch and brings the group relays 614, 615 and 616 and the control relays 619, 620, 621, 617, 622 and 623 into play to bring about the extension of a connection through the sender selector switch 600 to the allotted idle register sender.

With relays 616 and 617 operated a circuit is closed from battery through the winding of the vertical magnet 635, contacts of relays 616 and 617, contact of relay 622, conductor 636 to ground. Magnet 635 operates and brings about the energization of relay 612, which in turn, locks in a circuit including the relay 621. Relay 617 also closes a circuit from battery through the winding of vertical magnet 631, brush 627 of allotter 626, contact of slow relay 625, left contact of relay 623, outer right contact of relay 617 to ground over conductor 636. The magnet 631 operates and closes a locking circuit through its winding and contact and the winding of relay 623, the latter relay, however, remaining deenergized due to the shunt around its winding. Magnet 631 also closes a circuit from ground through its outer contact, conductor 638, through the brush 628, contact and winding of magnet 624, winding of relay 625 to battery and ground. Magnet 624 steps the switch 626 forward to the set of terminals representing the next idle sender and in so doing removes the shunt around the winding of relay 623. Relay 623 opens the circuit of slow relay 622 which commences to release.

During the interval relay 622 is deenergizing a circuit is closed from ground over conductor 636, inner right front contact of relay 623, right contact of relay 621, left front contact of relay 612, front contact of relay 611, assuming the link 608 to be busy, back contact of relay 609, winding of the horizontal magnet 610 to battery. Magnet 610 operates the switch and connects the incoming trunk conductors through the link 607 to the group of conductors 632 leading to the selected idle sender. Immediately that the connection is established a circuit is closed from battery through the winding of relay 201, conductor 210, through contacts of the switch, conductor 638 to ground at the contact of the magnet 631.

Relay 201 operates and opens the circuit of relay 613 which causes the deenergization of relays 612 and 619, provided no other sender is being sought through the same vertical group. Relay 201 also closes a holding circuit for the relay 204 which maintains a holding ground on the conductor 150. Furthermore, relay 201 connects the tip and ring conductors of the trunk through the sender selector switch to the impulse relay 700 of the sender. This results in the closure of a circuit from battery through the resistance 718, winding of relay 700, outer left contact of relay 703, conductor 640, through the sender selector 600 to conductor 641, outer right contact of relay 201, conductor 149, thence through the line switch 100 and the subscriber's substation and returning over the other side of the line to conductor 148, to the inner right contact of relay 201, conductor 642, through the sender selector 600, conductor 643, inner left contact of relay 703, right-hand winding of the balancing coil 701 to ground. Relay 700 operates and closes a circuit for the slow-to-release relay 702. Relay 702 places ground on the holding conductor 720. This ground potential is transmitted by way of conductor 638 and results in a holding circuit for the magnet 610 and relays 609 and 201 in substitution of the circuit temporarily maintained by the vertical operating magnet 631.

Following the series of operations just related, slow relays 136 and 622 become deenergized. Relay 136 opens the circuits of relays 130 and 135. Relay 130 opens the circuit of vertical magnet 116 and relay 135 opens the holding circuit of magnet 118 and relay 137. Magnet 116 causes the release of relays 134 and 122. Relay 122 removes the shunt and lets relay 127 operate. With the magnets deenergized the connection is now held through the line switch 100 due to the maintained energization of the magnet 125 which as above mentioned is held in a circuit closed to ground over the sleeve conductor 150.

Relay 622 in releasing similarly brings about a release of corresponding elements in the sender selector switch 600 and the connection through the sender selector is held by the magnet 610, the circuit of which is controlled by the slow relay 702 in the sender. 115

The apparatus is now in condition for receiving the first series of impulses. It will be recalled that the designation of the wanted line is A B 1 2 3 4. The letters A and B are abbreviations of the exchange name and represent two series of impulses which precede the numerical impulses. The letter A 125 may represent two impulses and the letter B three impulses. The calling subscriber, consequently, manipulates his impulse transmitter 163 to send a series of two impulses.

At the time relay 702 operates it closes 130

a circuit from battery through the winding of slow release relay 706, left back contact of relay 704, left contact of relay 705, conductor 720 to ground at the left contact of relay 702. Relay 702 also closes a circuit from battery through the resistance 739, left-hand winding of relay 707 to ground at the right contact of relay 702. Relay 707, however, does not operate since it is shunted by the following path: battery, resistance 739, through the right contact of relay 700 to ground at the right contact of relay 702.

In response to the first impulse relay 700 releases and opens the shunt around relay 707 and this latter relay operates. Relay 707 closes a circuit from battery through the winding of relay 704, outer left contact of relay 707 to the grounded conductor 720. Relay 704 operates and locks in a circuit 20 through its left front contact, left contact of relay 705 to the grounded conductor 720. Relay 704 opens the original circuit of relay 706 which latter relay, however, remains energized in a circuit traceable through the 25 outer right front contact of relay 707 to the grounded conductor 720. Relay 707 closes a circuit through the left-hand winding of relay 708 and relay 708 operates and closes a circuit from battery through its right-hand winding and right contact to the grounded conductor 720.

Relay 708 in operating completes a circuit from battery through its left-hand winding and left contact, conductor 724, outer right back contacts of counting relays 715, 714, 713 and 712 in series, winding of relay 712, outer left back contact of relay 713, conductors 725 and 726, outer right contact of relay 705, left front contact of relay 704, left contact of relay 705 to ground over conductor 720. So long as relay 707 remains operated, however, relay 712 is shunted and does not receive sufficient current in the circuit traced to energize. At the end 45 of the impulse, relay 700 operates and shunts relay 707 and this relay releases, opening the original circuit through the left-hand winding of relay 708. Relay 712 now operates in series with the left-hand winding of relay 708. Relay 712 locks in a circuit from battery over conductor 727, inner right contact of relay 712, winding of said relay, left back contact of relay 713 to ground over conductor 725.

It should be noted at this point that the armatures of the counting relay 712, and this is true of the remaining counting relays, are so arranged that the inner right contact is closed slightly in advance of the 60 opening of the outer right back contact. By this arrangement the locking of the relay is sure to occur before the energizing circuit is opened.

Immediately that the relay 712 opens its 65 back contact the circuit through the left-

hand winding of relay 708 is opened. Relay 708 is wound differentially and when the left-hand winding is opened the effect of the right-hand winding is to cause a quicker release. In response to the second impulse 70 of the series relay 713 is energized and locked in a similar manner and at its left contact opens the holding circuit of relay 712.

After an interval has elapsed following the series of impulses relay 706 becomes de-energized and a circuit is completed from ground over conductor 720, contact of relay 706, right contact of relay 704, inner right contact of relay 705, conductor 722, back contact of relay 807, winding of relay 808 to battery. Relay 808 operates and connects the control leads from the counting relays through to the first office register 800. Relay 808 also completes a circuit from battery through its winding and inner upper contact, conductor 818, winding of relay 705, right contact of relay 704, contact of relay 706 to grounded conductor 720. Relay 705, however, does not operate since it is shunted by the path previously traced.

With the counting relay 713 energized a circuit is closed from ground over conductors 726 and 725, outer left front contact of relay 713, conductor 730, conductor 822, contact of relay 808, winding of register relay 803, winding of relay 806 to battery. Relay 806 completes a circuit from battery, through the winding of relay 807, left contact of relay 806, conductor 821 to ground over conductor 720. Relays 806 and 803 100 lock to conductor 821. Relay 807 opens the shunt around relay 705 and this relay operates in series with relay 808. Relay 705 opens the holding circuit of relay 704 and relay 704 releases to in turn open the circuit of relay 705 and relay 808. Relay 808 releases and disconnects the control leads from the register 800. With relays 704 and 705 deenergized relay 706 again operates.

The subscriber manipulates his dial to 110 transmit the second series of three impulses and in a manner similar to that already explained, relays 712, 713 and 714 are operated. Relays 712 and 713 release in succession while relay 714 remains energized. After the proper interval has expired following the second series of impulses, relay 706 again becomes deenergized and a circuit is closed from ground by way of conductor 722 as above traced through the 115 front contact of relay 807, back contact of relay 814, winding of relay 815 to battery. Relay 815 operates and closes a holding circuit through its winding, over conductor 818, through the winding of relay 705 to ground as previously explained, relay 705 remaining deenergized due to the shunt. Relay 815 connects the control leads through to the second office register 801.

Since the counting relay 714 is now ener- 130

gized a circuit is established from ground, over conductor 725, through the outer left front contact of relay 714, conductor 729, conductor 820, through contact of relay 815, 5 windings of relays 809 and 813 to battery. Another circuit is closed from ground, over conductor 725, through the inner left contact of relay 714, conductor 730, conductor 822, through contact of relay 815, winding 10 of relay 810, winding of relay 813 to battery. Relays 809 and 810 lock through the left contacts to ground over conductors 823 and 821. Relay 813 closes a circuit for relay 814 which latter relay locks through 15 its contact to the grounded conductor 823. Relay 814 removes the shunt from relay 705 which operates in series with relay 815. Following, this, relay 704 releases and in turn releases relays 705 and 815.

20 The subscriber next transmits the third series consisting of one impulse representing the first digit of the numerical part of the designation. In response to this impulse relay 712 operates and at the end of 25 the proper interval a circuit is completed similar to the one above traced over conductor 722, through the front contacts of relays 807 and 814, back contact of relay 908, winding of relay 907 to battery. Relay 907 operates and closes a holding circuit through its winding and upper contact, thence over conductor 818, through the winding of relay 705 to ground as explained.

30 With the first counting relay 712 operated and relay 907 energized a circuit is completed in the manner above traced by way of conductor 729 to conductor 820, through a contact of relay 907 and thence 35 in parallel through the windings of relays 904 and 927 and through the winding of relay 923 to battery. These relays all lock in circuits traceable through the inner left front contact of relay 904, conductor 928 to the grounded conductor 821. Relay 927 40 closes a circuit from the grounded conductor 928, through its contact and the winding of relay 908. Relay 908 operates and locks through its inner left contact to the 45 grounded conductor 821. Relay 908 opens the shunt around relay 705 following which the above mentioned operations take place.

50 The subscriber now transmits the next series consisting of two impulses at the end 55 of which the counting relay 713 remains operated and after an interval relay 706 becomes deenergized. As explained a circuit is completed over conductor 722 through the front contacts of relays 807, 814 and 60 908, right back contact of relay 912, winding of relay 911 to battery. Relay 911 connects the control leads through to the hundreds register 901 and completes a locking circuit by way of conductor 818, through the winding of relay 705.

With counting relay 713 operated and relay 911 energized a circuit is established as hereinbefore traced over conductor 730, conductor 822, through the contact of relay 911, winding of register relay 910 to battery. 70 Relay 910 operates and locks through its inner left contact to ground over conductors 929 and 821. Relay 910 closes a circuit from battery through the winding of relay 912, through the outer left contact of relay 75 910 to the grounded conductor 821. Relay 912 locks to the conductor 821 and opens the shunt around relay 705 whereupon the operations already explained take place.

In response to the next series of impulses 80 consisting of three impulses the counting relay 714 is energized and after an interval a circuit is closed over conductor 722, through the front contacts of relays 807, 814, 908 and 912, right back contact of relay 916, winding of relay 915 to battery. Relay 915 connects the counting relays to the tens register 902 and closes a locking circuit by way of conductor 818 and the winding of relay 705 to ground. With 90 counting relay 715 operated and relay 915 energized circuits are completed as above traced by way of conductors 729 and 730, conductors 820 and 822, respectively, thence through contacts of relay 915 and windings 95 of register relays 913 and 914 to battery. Relays 913 and 914 lock to ground over conductors 930 and 821. Relay 913 closes an obvious circuit for relay 916 and this latter relay locks through its left contact to the 100 grounded conductor 821. Relay 916 causes the energization of relay 705 following which the same operations take place in the control circuit of Fig. 7.

Finally the subscriber transmits a series 105 of four impulses representing the last digit of the number and in response thereto the counting relay 715 is operated and remains energized. The holding circuit of relay 715 may be traced from battery through the inner right contact and winding of said relay, outer left back contact of relay 716 to ground over conductor 726. Following the necessary interval relay 706 becomes deenergized and the above traced circuit is completed by way of conductor 722 and the front contacts of relays 807, 814, 908, 912, 916, right contact of relay 920, winding of relay 110 919 to battery. Relay 919 connects the counting relays to the register 903 and prepares a holding circuit for itself by way of conductor 818 and the winding of relay 705. With relay 715 and relay 919 operated a circuit may be traced from ground over conductors 726 and 725, outer left back contact of relay 712, inner left contact of relay 715, conductor 731, conductor 932, through the contact of relay 919, winding of register relay 918 to battery. Relay 918 operates and locks through its inner left contact to ground 115 120 125 130

over conductors 933 and 821. Relay 918 at its outer left contact closes a circuit for relay 920 which latter relay locks to the grounded conductor 821. Relay 920 removes the shunt from relay 705 and relay 705 operates and causes the release of relay 704, which in turn, causes the release of relays 705 and 919.

As soon as the thousands digit is recorded 10 on the register 900 the sender is connected to the district marker in order that the record on the A and B office registers 800 and 801 may be transferred to the registers 1101 and 1102 in the district marker for determining 15 the group selective operation of the district switch 300. When relay 908 operates it completes a circuit from ground, over conductor 821, through the outer left contact of said relay, conductor 824, winding of relay 209 to battery. Relay 709 operates and locks 20 through its outer contact to the grounded conductor 720. Relay 709 closes a circuit from ground conductor 720, through the outer left contact of relay 711, inner contact 25 of relay 708, conductor 732, winding of relay 1004 to battery. Relay 1004 closes a circuit ground through its right contact, right contact of relay 1007, winding of relay 1008 to battery. Relay 1008 operates and completes 30 a circuit from battery through the right hand winding of relay 1003, left contact of relay 1004, left back contact of relay 1006, assuming that the sender corresponding to 35 relay 1006 is not attempting connection, outer contact of relay 1008, middle back contact of relay 1009, conductor 1014 to ground at the contact of slow relay 1012. Relay 1003 closes a circuit for relay 1007 which operates and opens the original circuit of relay 40 1008. This latter relay is held temporarily, however, in a circuit through the middle back contact of relay 1009. With relay 1007 operated relay 1003 locks through its left hand winding, left back contact of relay 45 1005, left contact of relay 1007, winding of relay 1009, conductor 1014 to ground through the contact of relay 1012. Relay 1009 operates and opens the holding circuit of relay 1008. A circuit is now closed for 50 the multi-contact relay 1001 leading through the inner right contact of relay 1003, innermost contact of relay 1009 to the grounded conductor 1014. Relay 1001 closes a circuit through its contact and the outermost contact of relay 1009, inner left back contact of relay 1011, winding of relay 1010 to battery.

With the sender thus connected to the district marker a circuit is established for the 60 particular vertical magnet 315 controlling the row of vertical contacts which represent the trunk 114 in the district switch 300. This circuit may be traced from the grounded conductor 1014, through the middle front contact of relay 1009, outer left front contact

of relay 1010, conductor 1017, contacts of relay 1001, conductor 1018, inner left contact of relay 711, conductor 733, through contacts of switch 600, conductor 645, outer right contact of relay 205, conductor 212, 70 winding of vertical magnet 315 to battery. Magnet 315 operates and prepares the contacts in the vertical row 308. Magnet 315 also closes as circuit through its right contact, conductor 322, windings of multi-contact relays 1223, 1220 and 1226 in parallel and battery. The purpose of these relays, which are individual to the district switch 300 will be described hereinafter. Magnet 315, furthermore, closes a circuit from battery through the winding of relay 208, conductor 213, left front contact of magnet 315, conductor 215, inner left contact of relay 201 to the grounded conductor 150. Relay 208 operates and locks through its outer 85 right contact.

The transfer of the record on the registers 90 and 801 to the marker will now be described. Since relay 1010 is operated a circuit may be traced from ground over conductor 1014, through the right contact of said relay, conductor 1015, through the relay 1001, conductor 1016, thence through the right contact of relay 803, conductor 825, contact of relay 1001, conductor 1019, winding of relay 1112 to battery. Another branch of this circuit extends from conductor 1016, through the right contacts of relays 809 and 810, conductors 826 and 827, 100 respectively, through the relay 1001, conductors 1020 and 1021, respectively, windings of relays 1107 and 1108 to battery.

The thousands register 900 being positioned also determines the operation of one 105 of the relays 1115, 1116, 1117, etc. Since the thousands digit is 1 and only the relay 904 is operated, a circuit is closed for the relay 1118 as follows: Grounded conductor 1016, thence through the outer right back contact of relay 922, right back contacts of relays 936, 935 and 905, thence through the inner right back contact of relay 922, conductor 937, through the relay 1001, conductor 1022, winding of relay 1118 to battery. 115

With the register relay 1112 operated a circuit is closed from the grounded conductor 1014, through the right contact of relay 1010, contact of slow-to-release relay 1040, conductor 1023, inner right back contacts of relays 1114 and 1113, inner right front contact of relay 1112, inner left back contact of relay 1111, winding of multi-contact relay 1106 to battery. With relays 1107 and 1108 of register 1102 operated a circuit is closed over the grounded conductor 1023, through the inner right back contacts of relays 1110 and 1109, inner right front contact of relay 1108, inner left front contact of relay 1107, winding of multi-contact 125 130

relay 1103 to battery. It will be obvious that when different combinations of the register relays 1101 and 1102, different combinations of the multi-contact relays of the 5 translator device 1100 may be selected. These multi-contact relays may be wired in any arbitrary fashion to give the selections required.

In the present case a selecting circuit is 10 completed from ground through the inner left contact of relay 1010, conductor 1024, through contacts of the relay 1106 to conductor 1120, through contacts of the relay 1103, contact of relay 1118, back contact 15 of relay 1119, conductor 1121, winding of group relay 1232 to battery. Relay 1232 relates to the group of trunks which occupies the section 302 of the vertical row 311 outgoing from the district switch 300 20 and leading to the terminal switching group having access to called lines whose thousands digit is 1. At the time relay 1010 operates a circuit is closed over grounded conductor 1014 to the middle front contact 25 of relay 1009, outer left front contact of relay 1010, conductor 1025, outer left back contact of relay 1246, winding of slow-to-release relay 1248 to battery. Relay 1243 closes a circuit for the slow-to-release relay 30 1247. When relay 1232 operates it closes a circuit from ground through its lowermost contact, winding of relay 1246 to battery. A circuit is now completed from ground through the inner left front contact 35 of relay 1246, right front contact of relay 1247, upper front contact of relay 1232, conductor 1221, contact of relay 1226, conductor 1224, winding of magnet 318 to battery. Magnet 318 prepares the contacts 40 in the vertical row 311. Magnet 318, moreover, closes a circuit from ground through its contact, common conductor 334, contact of relay 1226, conductor 1227, winding of relay 1249 to battery.

45 At the time relay 1246 operates it opens the holding circuit of relay 1248 which commences to release. During the release period of relay 1248 the test relays 1200 are connected in a manner about to be described to the test conductors of the selected outgoing trunks and the test conductors of the corresponding horizontal links to ascertain an idle trunk and the corresponding idle link. To connect these relays to the 50 test conductors of the outgoing trunks the multi-contact relay 1215 individual to the group of trunks involved is operated over the following circuit: battery, through the winding of said relay, through the middle lower contact of relay 1232, conductor 1233, contact of relay 1226, conductor 1234, left contact of relay 1247, outer left front contact of relay 1246 to ground over conductor 1025. Relay 1215 connects the right hand 55 windings of the double wound test relays of

the group 1200 to the respective test conductors of the outgoing trunk. The left hand windings of these relays are connected through the contacts of relay 1223 to the test conductors of the corresponding horizontal 70 links. If, for example, the first or lowermost trunk in the section 302 of the vertical row 311 is busy, a circuit is closed from grounded sleeve conductor 335, through contact of relay 1215, right contact of relay 1240, right hand winding of test relay 1242 to battery. Relay 1242 operates and locks through its right hand winding, conductor 1235, outermost right contact of relay 1246, to ground. If the corresponding horizontal 75 link 336 is busy a circuit is also closed from the sleeve conductor of the link by way of conductor 337, contact of relay 1223, outer left back contact of relay 1240, left hand winding of relay 1242 to battery. 80 Either winding of any test relay is sufficient to operate the same.

Provided the trunk 339 and its corresponding link 338 are both idle, the corresponding test relay 1245 remains deener- 85 gized.

After an interval the relay 1248 releases and a circuit is closed from ground over conductor 1025, right contact of relay 1249, right contact of relay 1248, inner right contact of relay 1246, conductor 1237, thence through the contacts of relay 1215, inner left front contact of relay 1241, inner left back contact of relay 1244, winding of relay 1243 to battery. It will be noted that 90 relay 1241 operates in a circuit closed through the left contact of test relay 1242 to ground over conductor 1245. With relay 1243 operated a circuit established from ground through the left contact of relay 100 1249, conductor 1238, contacts of relay 1215, right front contact of relay 1241, right back contact of relay 1244, left front contacts of relay 1243, through the contacts of relay 1223, thence over conductors 105 1250 110 and 1251, through the windings of horizontal operating magnet 324 to battery. The magnet 324 operates and effects connection between the incoming trunk 114 and the idle outgoing trunk 339 by way of link 115 338. Immediately that the connection is established the magnet 324 is locked in a circuit through its right hand winding, contacts of switch 300 to the grounded test conductor 150.

After an interval following the release of relay 1248 relay 1247 becomes deenergized and in so doing opens the circuit of relay 1215 whereby the test relays are disconnected from the outgoing group trunks. Relay 1247 also opens the circuit of vertical magnet 318. Magnet 318 causes the release of relay 1249. With relay 1247 deenergized a circuit is closed from ground through the inner left contact of relay 1246, right back 120 125 contact of relay 1247, outer left front contact of relay 1246 to ground over conductor 1025. Relay 1215 connects the right hand windings of the double wound test relays of

contact of relay 1247, conductor 1252, winding of relay 1011 to battery. Relay 1011 causes the release of the district marker which is no longer required. Relay 1011 in operating closes a circuit for relay 1012, but this relay being both slow-to-operate and slow-to-release requires an interval of time before it attracts its armature. During this interval a circuit is closed from ground over conductor 1014 through the outer left contact of relay 1011, conductor 1027, contacts of relay 1001, conductor 1028, winding of relay 711 to battery. Relay 711 operates and locks to the grounded conductor 720.

Relay 1011 also opens the circuit of relay 1010 which releases and opens conductors 1024 and 1025. After a further interval relay 1012 operates and removing ground from conductor 1014 causes the release of the operated relays in Fig. 10 and the disconnection of the district marker from the register sender by the release of multi-contact relay 1001.

25 The vertical magnets 315 and 318 having been deenergized, the connection through the district switch is held by the maintained operation of the horizontal magnet 324. When magnet 315 releases a circuit is closed from battery through the winding of relay 205, inner right contact of relay 208, conductor 214, left back contact of magnet 315, conductor 215, through the inner left contact of relay 201 to the grounded conductor 150. Relay 205 operates and locks through its inner right contact.

With relay 711 operated a circuit is closed from ground through the outer left contact of relay 920, conductor 940, outer right contact of relay 750, inner left contact of relay 710, inner right contact of relay 711, conductor 735, windings of relays 941, 921 and 922 in parallel to battery. Since the thousands digit is 1 and only 40 the register relay 904 of register 900 is operated, a circuit is now completed through a front contact of one of the relays 921 and 922 for operating the relay 1312 to cause the connection of the register sender to the line marker, shown in Figs. 13 and 14, which controls the final group switching equipment having access to the No. 1 thousand lines. This circuit leads from ground over conductor 735 as previously traced through 50 the outer right front contact of relay 922, thence through the right back contacts of relays 936, 935 and 905, inner right front contact of relay 922, conductor 942, winding of relay 1312 to battery. Relay 1312 55 operates and closes a circuit for relay 1316. Relay 1316 closes a circuit from ground through the contact of slow relay 1317, conductor 1339, outer right back contact of relay 1314, left contact of relay 1316, left contacts of relays 1340 and 1312, right hand

winding of relay 1310 to battery. Relay 1310 operates and closes a circuit for relay 1315. Relay 1315 closes a circuit from battery through the left winding and left contact of relay 1310, left back contact of relay 1311, left contact of relay 1315, winding of relay 1314 to the grounded conductor 1339. Relay 1314 operates and a circuit is closed from battery through the winding of multi-contact relay 1308, outer right contact of relay 1310, inner left contact of relay 1314 to conductor 1339. Relay 1308 operates and connects the leads from the register sender through to the line marker. Relay 1308 also closes a circuit through its contact and the outer left contact of relay 1314, left back contact of relay 1319, winding of relay 1318 to battery.

A circuit is now closed from ground over conductor 1339, through the inner right contact of relay 1314, contact of relay 1318, conductor 1341, through the contacts of relay 1308, conductor 1342, contact of relay 941, conductor 943, outer right contact of relay 710, conductor 737, through contacts of switch 600, conductor 646, outer left contact of relay 205, outer left front contact of relay 208, over the tip conductor of trunk 114, through the switch 300 to the tip conductor of trunk 339, thence through the contact of relay 418, winding of the vertical magnet 406 to battery. Magnet 406 operates and closes a circuit for relay 412 which connects the test relays of the marker to the horizontal links of the switch 400 for testing purposes.

The record of the thousands, hundreds, tens and units digits is now transferred from the registers of the sender to the line marker. The relays 1418 and 1419 in the line marker serve to determine whether the thousands digit is even or odd according to the combination in which they are operated. In the present case the thousands digit being 1 and odd; the relay 923 alone in the sender is operated and causes the closure of a circuit from ground over the conductor 1342 as above traced through the contact of relay 923, conductor 938, through contacts of relay 1308, conductor 1343, winding of relay 1418 to battery. A circuit is now closed from battery through the winding of multi-contact relay 1428, left front contact of relay 1418, back contact of relay 1419 to ground over conductor 1341.

Another circuit may be traced from ground over conductor 1342, through the right contact of register relay 910, conductor 944, through contacts of relay 1308, conductor 1345, winding of relay 1415 to battery. Other circuits are traceable over the grounded conductor 1342, through the right contacts of relays 913 and 914, conductors 945 and 946, contacts of relay 1308, conductors 1346 and 1347, windings of relays 1406 and 130

1407 to battery. Still another circuit leads from ground over conductor 1342, right contact of relay 918, conductor 948, contact of relay 1308, conductor 1348, winding of relay 5 1412 to battery.

With relay 1415 operated a circuit is traceable from ground over conductor 1341, inner right back contacts of relays 1417 and 1416, inner right front contact of relay 1415, inner 10 left back contact of relay 1414, winding of multi-contact relay 1426 to battery. A circuit is now established from battery through the winding of relay 1430, contact of relay 1428, contact of relay 1426, conductor 1432 15 to the grounded conductor 1341. Relay 1430 operates and a circuit is established from ground over conductor 1432, through the contact of relay 1430, inner right back contacts of relays 1409 and 1408, inner right 20 front contact of relay 1407, inner left front contact of relay 1406, conductor 1433, through contact of relay 1428, contact of relay 1426, conductor 1434, winding of vertical magnet 515 to battery. Magnet 515 25 operates and prepares the contacts in the vertical row 525. Magnet 515 also closes parallel circuits for the multi-contact relays 416 and 1420. Relay 416 connects the common test relays with the group of trunks 30 leading from the switch 400 to the connector switch 500 and also closes a circuit for the vertical operating magnet 408. The magnet 408 prepares the contacts in the associated row and also closes a circuit from ground 35 through contacts of relay 412, conductor 423, winding of slow-to-release relay 1321 to battery. Relay 1321 closes a circuit from battery, through the winding of slow-to-release relay 1338, back contact of relay 1337, outer 40 contact of relay 1321 to the grounded conductor 1341. Relay 1338 closes a circuit from ground, over conductor 1341, through the front contact of said relay, winding of slow-to-release relay 1323 to battery. Relay 45 1323 closes a circuit for relay 1324, which in turn, closes a circuit for relay 1325.

Relay 1420 connects the register 1401 to the connecting device 510. Relay 1420 also closes a circuit from battery through the 50 winding of relay 1435, contact of relay 1420 to ground over conductor 1341. Relay 1435 completes a circuit from the grounded conductor 1431, through its contact, thence 55 through the inner right contact of relay 1413, inner right front contact of relay 1412, conductor 1436, contact of relay 1420, winding of multi-contact relay 511 to battery. Relay 511 associates the test relays 1422, 1424, etc., with the horizontal links of the group 60 having access to the called subscriber's line 516 in the switch 500.

The testing operation will now be explained. If the first trunk 420 in the selected group is busy, a circuit is closed from battery through the right hand winding of 65

test relay 1334, inner right contact of relay 1336, through contacts of relay 416 to the grounded test conductor of trunk 420. If the link 403 associated with this trunk is busy a circuit is closed through the left hand 70 winding of test relay 1334, outer left back contact of relay 1336, through contacts of relay 412 to the grounded test conductor of link 403. Either winding of the relay 1334 is sufficient to operate the same. If the next 75 trunk 421 or its associated link or both be busy, the corresponding test relay 1331 is operated. Assuming, however, that the next trunk 422 and link 405 are idle, the relay 1328 remains deenergized. Relays 1334 and 80 1331 in operating lock through their right hand windings by way of conductor 1349, through the outer contact of relay 1321 to the grounded conductor 1341. Relays 1334 and 1331 complete obvious circuits for the 85 relays 1335 and 1332.

Another circuit may be traced from ground over conductor 1341, through the contact of relay 1321, conductor 1350, left front contacts of relays 1335 and 1332, left 90 back contact of relay 1329, winding of relay 1330 to battery. A circuit is now closed for the vertical operating magnet 513 at the connector switch 500. This circuit leads from ground over conductor 1341, through 95 the contact of relay 1321, outer right contact of relay 1330, middle right contact of relay 1329, contact of relay 416, conductor 424, winding of magnet 513 to battery. Magnet 513 prepares the associated contacts for 100 operation. Magnet 513, moreover, closes a circuit from ground through its contact, conductor 518, contact of relay 416, conductor 425, winding of relay 1337 to battery. Relay 1337 operates and opens the circuit of 105 relay 1338; this latter relay however, is slow-to-release and requires an interval before it retracts its armatures. Relay 1337 also closes a circuit from battery through the winding of the horizontal test magnet 110 509, contact of relay 511, conductor 527, front contact of relay 1337, contact of relay 1321 to ground over conductor 1341. Magnet 509 operates the test link 503 connecting the sleeve conductor of the incoming trunk 115 to the sleeve conductor of the proper one of the lines to which the links 501 and 502 have access.

While the foregoing operations are taking place, a test was being made of the links 120 501 and 502 to determine an idle one. Assuming the link 501 is busy a circuit is completed from battery through the right hand winding of test relay 1422, left contact of relay 1421, contact of relay 511, conductor 125 528 to the grounded test conductor of the link 501. Relay 1422 operates and locks through its left winding to conductor 1341. If the next link 502 is idle the corresponding relay 1424 remains deenergized. 130

After the necessary interval relay 1338 becomes deenergized and opens the holding circuit of relay 1323. While relay 1323 is holding its armature attracted a test circuit 5 is closed from battery through the winding of test relay 1322, left contact of relay 1323, back contact of relay 1338, middle right contact of relay 1330, outermost contact of relay 1329, contact of relay 1416, conductor 10 427, sleeve conductor 428, through contacts of the switch 500, over the test link 503 to the test conductor 521 of the called line 516. Assuming the line 516 to be idle, no potential 15 is found on this conductor and the test relay 1322 fails to operate. After an interval relay 1323 releases and opens the circuit of relay 1324. While relay 1324 which is slow to release is deenergizing a circuit is closed from ground over conductor 1341, 20 right back contact of relay 1323, right contact of relay 1322, outer left contact of relay 1325, inner right front contacts of relays 1335 and 1332, inner right back contact of relay 1329, left front contacts of relay 1330, 25 through contacts of relay 412, windings of horizontal magnet 411 to battery. Magnet 411 operates the selector switch 400. Immediately that the switch 400 operates a circuit is closed from battery through the winding 30 of relay 419, through contacts of the switch 400, thence through contacts of relay 412 to ground over the path just traced. Relay 419 operates and locks to the grounded sleeve conductor of the incoming trunk. Magnet 35 411 also locks through its right winding, contacts of switch 400, thence through the left contact of relay 419 to the grounded sleeve conductor. Relay 419 also closes a circuit for the relay 418 which opens the circuit of vertical magnet 406.

Another branch of the circuit above traced leads through the inner left contact of relay 1325, conductor 1352, right front contact of relay 1422, right back contact of relay 1424, 45 winding of relay 1423 to battery. Relay 1423 operates and a grounded circuit is extended through its right contact, over conductor 529, contact of relay 511, left winding of magnet 508 to battery. Magnet 508 50 operates the connector switch 500 and locks through its right winding and contacts of said switch to ground over the sleeve conductor 428. After an interval has elapsed relay 1324 releases. Relay 1325 remains energized in a locking circuit through its inner 55 right contact to the grounded conductor 1351. A circuit is next completed from ground over conductor 1351, though the back contact of relay 1324, outer right contact of relay 1325, winding of release relay 1319 to battery. Relay 1319 closes a circuit for relay 1317, which being slow to operate requires an interval to attract its armature. Relay 1319 also opens the circuit of relay 60 1318 which removes ground from the con-

ductor 1341, bringing about the release of the several relays which have been held in circuit depending upon this grounded conductor. While relay 1317 is operating a circuit is closed from ground through its contact, right contact of relay 1319, conductor 1353, contact of relay 1308, conductor 1354, winding of relay 710 to battery. Relay 710 locks to the grounded conductor 720.

After an interval relay 1317 operates and removes ground from conductor 1339 causing the release of the remaining operated relays and magnets in the line marker mechanism. Relay 1308 is also released to disconnect the register sender from the line 75 marker. The horizontal test magnet 509 releases and disconnects the test link 503 from the subscribers' lines and from the trunk 422. With the vertical magnets 406, 408, 513 and 515 deenergized the connection 80 is held through the switches 400 and 500 by the maintained operation of magnets 411 and 508.

Relay 710 in operating brings about the operation of relay 703 which causes the release of the sender. The circuit for relay 90 703 leads from battery through the winding thereof, outer left contact of relay 710, outer right contact of relay 750, conductor 940 to ground at the outer left contact of relay 920. Relay 703 opens the holding circuit of relay 700 which releases and opens the circuit of relay 702. After an interval relay 702 releases and removes ground from the holding conductor 720 whereby all energized relays 95 of the registers and all other relays locked to the conductor 720 are released. With the removal of ground from conductors 720 and 638 the horizontal magnet 610 of the sender selector is deenergized whereby the sender 100 105 is disconnected from the trunk.

The removal of ground from conductor 638 and the release of the switch 600 also opens the holding circuit of relay 201. Relay 201 extends the tip and ring conductors 110 of the trunk 114 through to the repeating coil 227. The extension of the line through to the repeating coil closes a circuit for relay 203 which operates and affords a substitute circuit for relay 204, since the 115 circuit which previously held the relay 204 has now been opened at the outer left front contact of relay 201. Relay 201 at its inner left contact also opens the holding circuits of relays 208 and 205. Relay 208 completes the tip and ring conductors of the trunk 114 through to the right hand windings of the repeating coil 227.

Release of the established connection.

After the conversation has terminated between the subscribers, they replace their receivers on the switchhooks and relay 203 becomes deenergized. After an interval 120 slow relay 204 releases and removes ground 125 130

from the sleeve conductor 150. This causes the deenergization of the operating magnet 125 of the line switch 100, relay 120, relay 146, the operating magnet 324 of the district switch 300, relay 419, the operating magnet 411 of selector switch 400 and the operating magnet 507 of the connector switch 500. The entire connection through the switches is thereby released and the apparatus is restored to its normal condition.

Called subscriber's line tests busy.

In case the line of the called line 516 is busy at the time a test thereof is made, the relay 1322 operates in the circuit previously traced and locks through its inner left contact to ground on conductor 1341. Relay 1322 closes a circuit from the grounded conductor 1341 through its outer left contact, conductor 1356, contact of relay 1301, conductor 1357, winding of relay 750 to battery. Relay 750 operates and locks to the conductor 720. Relay 750 closes a circuit from ground through the secondary winding of the busy tone coil 751, inner right contact of relay 750, left hand winding of the balancing coil 701, through the condenser 738 to ground. Current flowing in this circuit induces a current in the right hand winding of the coil 701 which is transmitted to the calling substation, producing a busy tone in the subscriber's receiver. After an interval relay 1323 releases, but since relay 1322 is now operated the above traced circuits for operating the selector switch 400 and the connector switch 500 are not completed. In the manner described relay 1324 releases and operates the release relay 1319 which brings about a disconnection of the sender from the district marker. In this case, however, relay 703 remains deenergized since the operating circuit thereof is now open at the outer back contact of relay 750. Consequently, the sender remains connected to the calling subscriber's line until he recognizes the significance of the busy tone and hangs up his receiver. On hanging up his receiver he opens the circuit of relay 700 which as above described brings about the release of the sender and the sender connector switch 600. Following this the line switch and district selector 300 are released in the manner explained.

Diverting traffic from given groups of switching apparatus.

Assume now that for some reason such as the existence of trouble in the district marker or the senders which pertain to a given division or group of district switches, it is desirable to divert calls extended through the line switches from this group of district switches and into other groups. As a specific instance, consider that trouble exists in the district marker shown in Figs.

10, 11 and 12, this marker controlling the group of district switches of which the district 300 is one. For this purpose a trouble desk illustrated within the rectangle 220 is equipped with one or more keys which serves 70 to render artificially busy all trunks outgoing from the line switches to district switches belonging to the particular group in question. The key 221 when actuated by the trouble operator places a ground potential on the first five points of the allotter switch 143 cooperating with the brush 154. These five points represent the first five trunks in the switch 100 which are assumed to lead into the group desired to be blocked. 80 Whenever, therefore, the allotter switch 143 is in any of these positions relay 155 operates. Relay 155 closes a circuit from battery through the winding of relay 139, winding and contact of magnet 138, contact 85 of relay 155 to ground. Magnet 138 advances the switch 143 until the brush 154 passes off the terminal grounded by the key 221. Relay 155 then releases and the allotter switch is now free to select the first idle 90 trunk leading into some other group or switching apparatus.

In case trunks from other line switches (not shown) lead into this same group the key 221 is provided with a multi-contact 95 which leads to terminals of the allotter switch associated with such other line switch in a manner similar to that shown in Fig. 1. Hence, the depression of key 221 renders non-selectable to the line switches all trunks 100 that lead into the particular district switches represented by the key 221.

In a similar manner other keys are provided at the trouble desk for diverting the traffic from other groups or divisions of district switches.

Assume next that trouble exists at some point beyond the district switches as in one of the terminal line groups of switch apparatus. If, for instance, the line marker 110 shown in Figs. 13 and 14 which controls the first terminal line group of switches is in trouble, it is desirable not to permit calls to be routed into this group but to extend them instead to an operator's position. To accomplish this, key 222 is actuated at the trouble desk 220. The key 222, being individual to the particular terminal line group concerned, so affects the district markers that whenever a call is received intended for the said terminal line group, it is automatically diverted to the operator's position 330. The key 222 closes a circuit from ground through its contact, conductor 223, winding 115 of relay 1119 to battery. In a similar manner parallel circuits may extend from the contacts of key 222 to relays similar to relay 1119 in the district markers pertaining to other groups of district switches provided these other district switches have access to 130

the terminal line group of apparatus involved.

Returning to the point where the translator 1100 is positioned to prepare a selecting circuit for the group relay 1232 which identifies the group of trunks in the district switch leading to the desired terminal line group, it will be found that this circuit now leads by way of conductor 1024 through 10 the translator 1100, contact of relay 1118, thence over the front contact of relay 1119, conductor 1122, winding of relay 1231 to battery. Relay 1231 operates and in a manner analogous to that already explained in 15 connection with relay 1232 determines the selection of an idle trunk in the vertical row 314 which leads to the operator's position 330 or to an equivalent operator's position. In the same manner as fully explained in 20 connection with the previous call, the present connection is routed to the answering operator at position 330 who converses with the calling subscriber and ascertains the number of the desired line and either notifies him 25 that the connection is unattainable or assists him in completing the connection by the usual manual cord circuits.

In order to divert the traffic from other terminal line groups of switching apparatus, 30 the trouble desk 220 may be equipped with keys similar to the key 222 which operate relays in the district markers similar to relay 1119 for automatically extending the selecting circuit through the translator 1100 to the relay 1231, whereby the district switch 35 routes the call to the operator's position.

For a better understanding of the detailed 40 operation of a system of this character, reference is made to the patent to S. B. Williams, No. 1,517,331, issued December 2, 1924.

What is claimed is:

1. In a telephone system, a number of 45 selective switches, means for directing incoming calls to said switches, a plurality of register senders and a common marker for governing the selective operation of said switches, and means for diverting away from said switches calls which are normally directed thereto.

2. In a telephone system, selective switches 50 arranged in groups, primary switches for directing calls to the selective switches of each group, register controlling mechanisms, one for each group of switches for governing the selective operation of any switch in such group, and means for diverting to other groups the calls normally directed into a given group of switches.

3. In a telephone system, selective switches 55 divided into groups, primary switches for directing calls to the switches of each of said groups, controlling mechanisms, one for each group of switches for governing the selective operation of any switch in the related group, and operator controlled means

for governing said primary switches so that calls normally directed into a given group of switches are diverted to other groups.

4. In a telephone system, selective switches arranged in groups, a number of primary 70 switches for routing calls through the selectors of each group, controlling mechanisms, one for each group of switches for controlling the selective operation of any switch in such group, and means for affecting all primary switches which route calls normally to a given group so that such calls will be routed to other groups of selective switches.

5. In a telephone system, a number of 80 groups of selective switches, means for directing incoming calls to the switches of each group, controlling mechanisms, one for each group of switches including a number of register senders and a common marker 85 for governing the selective operation of any switch in the corresponding group, and means for diverting to other groups the calls normally directed into a given group of switches.

6. In a telephone system, selective switches arranged in groups, means for directing calls to the switches of each group, other switches, controlling mechanisms, one for each of said groups for governing the selective operation of any switch in such group to further extend calls to said other switches, and means depending on the character of the call for influencing said controlling mechanisms to divert such call away from 100 said other switches.

7. In a telephone system, selective switches arranged in groups, means for directing calls to the switches of each group, other switches, controlling mechanisms, one for each group of switches for governing the selective operation of any switch in such group to further extend calls to said other switches, an operator's position, and means depending upon the character of the call for influencing said controlling mechanisms to divert such call away from said other switches and to route it to said operator's position.

8. In a telephone system, selector switches arranged in groups, means for distributing calls to the switches of each group, other switches, controlling devices, one for each group of said switches for governing the selective operation of any switch in such group to further extend calls to said other switches, an operator's position, and means for changing the manner in which the controlling device governs the switches of the corresponding group to divert calls normally intended for said other switches to the operator's position.

9. In a telephone system, selective switches arranged in groups, means for directing calls to the switches of each group, succeed-

- ing groups of switches, controlling mechanisms, one for each of said first groups for governing the selective operation of any switch in such group to further extend the 5 calls into said succeeding groups, and means controlled by said mechanisms when a call is received for a given one of said succeeding groups for diverting such call away from said succeeding group.
10. 10. In a telephone system, a number of groups of selector switches, means for routing calls to the switches of each group, succeeding groups of switches, controlling mechanisms, one for each of said first groups 15 for governing the selective operation of any switch in such group to further extend the call into said succeeding group, an operator's position, and manual means for altering the controlling mechanisms to influence their control over said selector switches so 20 that calls received for a given succeeding group are diverted away from said group and routed to the operator's position.
11. In a telephone system, selective switches, means for directing calls to said 25 switches, other switches, a controlling mechanism for governing said selective switches to further extend calls to said other switches, said mechanism comprising a plurality of register senders and a common marker, an 30 operator's position, and means for influencing said controlling mechanism to divert calls away from said other switches and to route them to said operator's position.
- In witness whereof, we hereunto subscribe 35 our names this 29 day of March A. D., 1923.

LEO KELLER.

SAMUEL B. WILLIAMS.
